SWEETENING HYDROCARBON OILS

Richard S. McClaughry and Louis V. Moore,
Hammond, Ind., assignors to Standard Oil
Company (Ind.), Chicago, Ill., a corporation
of Indiana

No Drawing. Application February 13, 1930
Serial No. 428,236

4 Claims. (Cl. 196—33)

This invention relates to a method of sweetening hydrocarbon oils and it pertains more particularly to the treatment of naphtha for use by paint and varnish manufacturers.

5 The naphtha thinner used in paints and varnishes must be sweetened to a higher degree than most hydrocarbon oils because it is used in combination with heavy metal soap driers which form black sulfides. Paints and varnishes 10 also come in contact with copper and other metals which are tarnished by small amounts of sulfur. The official sulfur test for gasoline adopted by the American Society of Testing Materials, which is often used as a sulfur test for naphtha, 15 is to immerse a copper strip in the naphtha at 122° F. for three hours. The Perdew test is to subject mercury to the naphtha, making use of the affinity of mercaptans for this metal. Recently, a more rigid test has been adopted, 20 namely, the du Pont test in which a bright copper strip is heated in naphtha at about 350° F. for one-half hour. Naphthas which meet the former tests do not always meet the rigorous du Pont test, and neither the doctor nor the 25 hypochlorite sweetening process heretofore used will give a product that will pass the du Pont test. The object of our invention is to provide a sweetening process for naphtha by which it can be made to meet the most rigorous requirements of paint and varnish manufacturers. 30

Other objects will be apparent as the detailed description of our invention proceeds.

Briefly we contemplate a combination sweetening process, wherein a treatment with doctor 35 solution is followed, after complete washing, by a special hypochlorite treatment, the hypochlorite solution containing about 0.2% of available chlorine, and being used in amounts so that the chlorine is practically used up and the solution 40 can be discarded after use.

To describe our invention in detail, we begin with a hydrocarbon oil, preferably a sour naphtha with a boiling range of 350 to 472° F. A 1,600-barrel batch of the sour naphtha is first treated 45 with about 75 barrels of sodium plumbite, preferably a solution containing 2-4% available lead. This is the reagent commonly referred to as "doctor" solution, and is prepared by dissolving lead oxide in sodium hydroxide in a manner well known in this art. In our process the doctor solution should be free from elemental sulfur and preferably should contain no bottom settling or precipitated lead sulfide.

After thoroughly mixing the naphtha with the doctor solution, the doctor solution is settled and

drawn off, and the naphtha is washed three or four times with water to remove traces of doctor solution, since lead compounds remaining in the oil are undesirable in the subsequent steps of the process.

The naphtha is then treated with from 30 to 150 barrels of a dilute solution of sodium hypochlorite (NaOCl) containing about 0.2% of available chlorine and about 0.2% excess sodium hydroxide (NaOH). The amounts of sodium hypochlorite solution required will depend upon the amount of sulfur impurities in the naphtha, and should be adjusted so that at the end of the treatment, the hypochlorite is practically spent. With distillate from Mid-Continent crude, we 70 have found that an amount of hypochlorite solution containing about 140 pounds of chlorine is required in the treatment of the batch herein described. After the hypochlorite treatment the oil must be thoroughly washed with water to 75 remove excess hypochlorite.

It would be difficult if not impossible to state all of the reactions that characterize this treatment. It appears, however, that doctor solution removes sulfur in the presence of excess mercaptans and not in the absence thereof. The first step, therefore, eliminates the sulfur and may leave lead mercaptides in solution. The hypochlorite treatment, while ineffective in removing sulfur, apparently converts the lead mercaptides 85 into harmless products. At any rate the combined treatment yields a sweet stable product that easily meets the du Pont test.

We do not rely upon any theories to explain why the combination of treatments set forth 90 will effect a sweetening which cannot be effected by either process applied by itself. The success of the combined process has, however, been demonstrated on a commercial scale and this new process is replacing the sweetening process here- 95 tofore used.

While we have described in detail a preferred embodiment of our invention, we do not limit ourselves to any of such details except as defined by the appended claims. Chloride of 100 lime or other hypochlorite may be used instead of the sodium hypochlorite, various concentrations of both hypochlorite and doctor solutions may be used, and other modifications may be 105 employed to suit the process to any particular refinery.

We claim:

1. The method of sweetening petroleum hydrocarbon naphtha so that it gives a negative test for sulfur when contacted with a polished copper 110

strip at 350° F. for thirty minutes, which comprises treating said naphtha with doctor solution in the absence of free sulfur, giving the treated naphtha a plurality of water washes and treating the naphtha with an alkaline hypochlorite solution.

2. The method for sweetening petroleum hydrocarbon naphtha for use in paint or varnish compositions so that said naphtha gives a negative test for sulfur when contacted with a polished copper strip at about 350° F. for thirty minutes, which comprises treating said naphtha with doctor solution in the absence of free sulfur, thoroughly washing said doctor solution out of the naphtha, and treating said naphtha with an alkaline hypochlorite solution.

3. The method of sweetening sour petroleum naphtha that boils within the range of 350 to 472° F. for use in paint and varnish compositions so that said naphtha gives a negative test for sulfur when contacted with a polished copper strip at 350° F. for thirty minutes which com-

prises treating said naphtha with a solution of sodium plumbite in the absence of free sulfur, giving the treated naphtha a plurality of water washes, treating the naphtha with sodium hypochlorite, and then washing the naphtha with water to remove the excess sodium hypochlorite.

4. The method of sweetening sour petroleum naphtha that boils within the range of 350 to 472° F. for use in paint and varnish compositions so that said naphtha gives a negative test for sulfur when contacted with a polished copper strip at 350° F. for thirty minutes, which comprises treating said sour naphtha with doctor solution in the absence of free sulfur, thoroughly washing out traces of the doctor solution, then treating said naphtha with an alkaline hypochlorite solution containing about 0.2% of available chlorine and then thoroughly washing the treated naphtha with water to remove excess hypochlorite solution.
